UNITED STATES PATENT OFFICE

KITARO KATOW, OF TOKYO, JAPAN

SASH BALANCE

Original application filed June 25, 1927, Serial No. 201,455. Divided and this application filed January 18, 1928. Serial No. 247,651.

My invention relates to improvements in windows and more particularly to windows of the kind comprising double-hung sashes, and is a division of my copending application for Windows, filed June 25, 1927, Serial No. 201,455.

One object of my invention is to provide means whereby a plurality of sashes can readily slide up and down either individually or jointly.

Another object of my invention is to obtain means for holding all of the plurality of sashes or either one of them at any desired heights.

A further object of my invention is to obtain means for providing counter-weights for the two sashes combined and also providing guide means for sash-cords, which guide means may function as either movable or stationary.

A still further object of my invention is to provide means for guiding the counter-weight and also for preventing it from any lateral movement, together with means for releasably restraining the counter-weight from its vertical movements to hold it at any desired height.

There are other objects and particularities of my said invention, which, together with the foregoings, will appear in the following descriptions, with reference to the accompanying drawings, wherein:

Fig. 1 is an inside elevational view of my window, partly in section and partly broken away.

Fig. 2 shows a sectional plan of a part taken at line II—II in Fig. 1.

Fig. 3 is a sectional plan view, in part, taken at line III—III in Fig. 1.

Fig. 4 is a detail plan showing one pair of the rollers which have fixed bearings.

In practising my invention, I provide a pair of sashes, each slidably guided in suitable grooves at its sides in the framework of window, and a sash-cord secured at the ends to the sides of the respective sashes, forming an open loop ending at the respective sashes.

The cord extends past a pair of stationary guide rollers mounted in the upper portion 50 of the framework and also a movable guide

roller intermediate the two stationary rollers. The movable roller is mounted on a weighted member, which is movable up and down within a side chamber in the framework, and is adapted to be releasably restrained from the movement, at will.

In order to facilitate a better understanding of my invention, the following descriptions are given with reference to the drawings.

Referring to the drawings, a window embodying my invention comprises, in general, a rectangular framework 1, having a plurality of usual longitudinal grooves in each of its vertical sides, and inner and outer sashes 3 and 4, for holding window-glasses therewith and adapted to slide up and down along the vertical grooves with their vertical side edges guided thereby, as usual.

At the top portion of each vertical side of the framework 1, there are disposed in parallel two stationary pulleys or guide rollers. One of such rollers is shown by the reference 5, the other being disposed behind the roller 5 on the common axis. The rollers may have 70 peripheral grooves. The counterweight 10 is adapted to travel up and down within a vertical side chamber formed in the framework 1 behind its grooved side. A rope or sash-cord 13 is provided extending between 80 the inner and outer sashes past the stationary rollers such as 5, and a movable roller 14 mounted on the counter-weight 10.

In each side chamber of the framework 1 is arranged a link structure 70. The structure may comprise a pair of levers 71 and 72, respectively pivoted in the upper and lower end portions of the weight chamber on the axis 73 and 74 respectively located therein by suitable bearings means, such as 75 and 76. 85 The respective ends of the levers 71 and 72 are operatively connected by a pair of vertical links 77 and 78. The lower lever 72 is provided with an arm portion, at the outer end of which one end of a rod 79 is operatively connected therewith. A similar link structure is connected to the other end of the rod 79.

The weighted member 10 is provided with side grooves 80 and 81 adapted to receive the 90

inner edge portions of the link 77 and 78, respectively. The weight 10 is suspended by the sash-cord 13, which extends from one end secured to one of the sashes through the stationary guide roller 5, past the rollers 14 and the other of the stationary rollers to the other end secured to the other of the sashes.

When the rod 79 is actuated to the left, the levers 72 and 71 are turned anti-clock-wise, and the links 77 and 78 are made to approach each other, thus shortening the distance therebetween, and the link edges will closely engage the grooves 80 and 81 with a sufficient pressure thereon to restrain the weighted member 10 from its vertical movements. When the rod 79 is actuated to the right, the braking action on the weighted member 10 will be released, as will be readily understood. With this arrangement, the window sashes may be operated to slide up and down either individually or jointly, and also the weighted members 10 may be properly guided by the links 77 and 78, enabling smooth operations of the sashes.

In order to facilitate the axial operation of the rod 79, a member 20 may be fixed to the rod 79. The member 20 has a cam surface 21, adapted to cooperate with the inner end of a handle lever 22 pivotally mounted on the bottom portion of the framework by means of a pin 23.

When the link structures are applied to the weight 10 when the latter is at any point, the rollers 14 carried thereby assume a corresponding fixed position. The respective ropes 13 may be considered, at present, as extending between the pair of sashes past the stationary rollers 5, the rollers 14, stationary at present, and the other stationary rollers in the top of the framework, in the order mentioned. Since the sashes form counter-weights for each other, when one of them is actuated to slide upwards, the other will be lowered just the same distance with the upward movement of the former sash, and they may take any desired relative positions.

In order to move both of the sashes 3 and 4 upwards or downwards simultaneously or jointly, the brake devices 70 may be released to permit free movements of the weighted members 10, and the sashes can be moved jointly to any desired height, for example, the upper-most position. In this case, the weighted members 10 function as the counter-weight for the both sashes combined, as they are now suspended from the sash-cords 13.

Each sash 3 or 4 may be operated individually and caused to assume any desired position independently of the other, as the weighted members will be lowered or raised just half the distance travelled by the individual sash by aid of the movable pulleys 14.

It will be seen that, since the weighted members 10 are restrained from any lateral

movement and vertically guided by means of the link structure 70, the sashes can slide up and down very smoothly.

Although I have shown a particular embodiment of my invention, it will be obvious to those skilled in the art that various modifications and changes may be made without departing from the spirits and scope of the invention, and I do not desire to limit the invention to the specific modification described, but only in so far as set forth in the appended claims.

Having now particularly described and ascertained the nature of my said invention and in what manner the same is to be performed, I declare that what I claim as my invention is:

1. A window comprising a frame having a side chamber, a pair of sashes vertically slidable in said frame, a weighted member vertically movable within a side chamber in said frame, a roller carried on said weighted member, a pair of guide rollers mounted above said side chamber and having fixed bearings, a sash-cord secured to one of said sashes and extending over one of said stationary rollers, engaging under said weight carried roller and over the other stationary roller and having the other end secured to the other sash, thus suspending said weighted member therefrom through said weight carried roller, a pair of vertical link rods in said side chamber for guiding the vertical movements of said weighted member therebetween, and means for moving said link rods toward and from each other for applying braking action on or releasing said weighted member.

2. A window comprising a frame having a vertical chamber at one side thereof, a pair of vertically slidable sashes in said frame, a weighted member vertically movable in said chamber, a roller revolvably mounted on said weight member and movable therewith, a pair of revolvable rollers above said chamber and having fixed bearings, a sash cord having its ends attached to the respective sashes, said sash cord passing over each of said pair of rollers and under said weight carried roller, a pair of braking and guiding link rods in said chamber and at opposite sides of said weight, a pair of links one having a fixed pivot in the upper end of the said chamber and the other having a fixed pivot in the lower end of said chamber, the said link rods being pivotally connected to the said links, and means to operate said links to cause the link rods to brake or release the weight.

In witness whereof I affix my signature. 125
KITARO KATOW.
